UNITED STATES PATENT OFFICE.

HADAR HALLSTRÖM, OF ESKILSTUNA, SWEDEN.

MANUFACTURE OF CUTLERY.

SPECIFICATION forming part of Letters Patent No. 274,318, dated March 20, 1883.

Application filed July 15, 1882. (No model.)

To all whom it may concern:

Be it known that I, HADAR HALLSTRÖM, of Eskilstuna, Sweden, have invented a certain new and useful Improvement in the Manufacture of Cutlery and Tools, of which the following is a full, clear, and exact description.

The object of my invention is to facilitate the manufacture of cutlery and like articles with hollow handles of iron or steel.

10 The invention consists in a handle for knives or other pieces of cutlery formed of two concaved or hollowed blanks, which are united by welding them together and to the knife or article itself, whereby a strong, durable, and light handle is formed, which cannot become detached from the knife or other article.

Reference is to be had to the accompanying drawings, forming part of this specification, in which similar letters of reference indicate corresponding parts in all the figures.

Figure 1 is a plan view of the handle-blank. Fig. 2 is a longitudinal sectional elevation of the same, showing it pressed between the dies. Fig. 3 is a cross-sectional elevation of the 25 pressed blank and the dies. Fig. 4 is a plan view of the pressed blank. Fig. 5 is a longitudinal elevation of the blank for the knife or other article of cutlery. Fig. 6 is a longitudinal sectional elevation of the same between the dies. Fig. 7 is a cross-sectional elevation of 30 the same between the dies. Fig. 8 is a longitudinal elevation of the pressed blank. Fig. 9 is a longitudinal elevation of the completed knife or fork between the dies. Fig. 10 is a cross-sectional elevation of the same.

A blank, *a*, of sheet-iron or steel, is placed between two dies, *A* and *B*, and hollowed out or concaved, and the concaved part is then punched out of the blank. In the same manner one end of a long blank, *b*, which has the length of the knife or fork, &c., is placed between the dies *C* *D*, is hollowed or concaved by the dies, and is then punched out on the dotted line. The pressed handle-blank *a*, or

the handle-blank *b*, must be a right-hand blank and the other a left-hand blank, so that when the open sides of the blanks are placed together a hollow handle will be formed, one-half of which is made integral with the knife or fork itself. The two handle-blanks, having 45 been placed against each other in the manner described, are then heated to the welding-heat, and are placed between two dies, *E* and *F*, and are subjected to blows or to pressure between the dies, whereby the two handle-blanks will be 50 welded together, and will form a hollow handle integral with the knife, fork, or other article. It is evident that both handle-blanks 55 can be made out of short strips of metal, and the two can both be welded to the blade. After 60 having been welded, the knives, forks, &c., and their handles, are finished, ground, and polished. Light, strong, and durable handles can thus be made very easily and rapidly, and they cannot become separated from the knife 65 or fork.

Handles for screw-drivers, chisels, gimlets, draw-knives, &c., can also be formed in the manner described above.

I am aware that it is not new to cut out the 70 blanks from sheet metal, or cast them into the desired form and then braze or solder them together; but

What I claim is—

The method of forming hollow metallic handles on knives or forks which consists in first compressing the handle-sections into a concave form, one being on the knife or fork blank, and then welding together the corresponding edges, substantially as described. 75

The foregoing specification of my improvement in the manufacture of cutlery and tools signed by me this 23d day of June, 1882.

HADAR HALLSTRÖM.
